Letters Patent No. 917. Dated July 21st 1857.

W W W W W W W W

The schedule referred to in these Letters Patent, and making part of the same.

.....

To all to whom these presents shall come:

Be it known that I, Henry Jenkins, of Brooklyn, in the County of Kings, and State of New York, have invented or produced a new and original ornamental design for Iron Railings; and I do hereby declare that the nature of the same is fully set forth in the following description and shewn in the annexed drawing making part of this specification; in which, a, a, a, are the horizontal rails of a flat shape, b, b, are curved bars forming double arch shapes between the lower bars a, a, c, c, are cast ornaments of the shape and configuration shewn, connecting the arch shaped bars at their intersections. — d, d, d, are cast ornaments of the configuration shewn, attaching the ends of the bars b, at the rails a. — e, e, e, are square vertical bars attached to the rails a, a, at the ornaments d, d, and the top of the railing is finished by lance pointed ornaments f, with the base similar to the ornaments d, as shewn.

I claim the Design of the ornamental iron railing composed of the arch shaped bars b, and ornaments c, d, and f, and bars, a & e, as described and represented in the drawing. —

In witness whereof, I have hereunto set my
signature this twenty sixth day of June 1857.
